United States Patent Office

Des. 221,784
Patented Sept. 7, 1971

221,784

ROLLING TOY

John A. Gale, 978 E. Shady Lane, Wayzata, Minn.
55391, and Donald Delone Heinz, 2403 Lincoln St.
NE., Minneapolis, Minn. 55418

Filed Mar. 18, 1970, Ser. No. 21,948

Term of patent 14 years

Int. Cl. D21—01

U.S. Cl. D34—15

FIG. 1

FIG. 2

FIG. 4

FIG. 3

FIG. 1 is a front perspective view of the rolling toy embodying our new design;

FIG. 2 is a side elevation thereof;

FIG. 3 is a view from one end thereof; and

FIG. 4 is a section view taken substantially along line 4—4 of FIG. 2.

We claim:

The ornamental design for a rolling toy, substantially as shown.
